UNITED STATES PATENT OFFICE.

BENJAMIN F. MCGUINNESS, OF SAUNDERSVILLE, MASSACHUSETTS, ASSIGNOR TO
CROMPTON & KNOWLES LOOM WORKS, A CORPORATION OF MASSACHUSETTS.

FILLING-DEPRESSOR FOR WEFT-REPLENISHING LOOMS.

1,070,712.

Specification of Letters Patent. Patented Aug. 19, 1913.

Application filed September 29, 1910. Serial No. 584,469.

To all whom it may concern:

Be it known that I, BENJAMIN F. MCGUINNESS, a citizen of the United States, residing at Saundersville, in the county of Worcester and State of Massachusetts, have invented certain new and useful Improvements in Filling-Depressors for Weft-Replenishing Looms, of which the following is a specification.

10 My invention relates to that class of weft replenishing looms which have a filling detector or feeler which is located on the magazine end of the loom, on the loom side or end, and comprises a feeler slide which feels 15 through an opening in the front wall of the shuttle, and engages with the filling on the bobbin or filling carrier in the shuttle on every second forward movement of the lay.

It has been found in practice that when a 20 shuttle has entered the stationary shuttle box at the magazine end of the loom on the forward movement of the lay and the filling detector or feeler slide is entering the opening in the front wall of the shuttle to 25 engage with the filling on the bobbin that the filling which passes from the shuttle to the fabric may take its position in front of or over the opening in the shuttle, and the filling detector or feeler slide, on entering 30 said opening, is liable to accidentally break or sever the filling thread.

The object of my invention is to prevent 35 the filling detector or feeler slide from accidentally breaking the filling thread in the running shuttle, in the manner above described.

My invention consists in a device or mechanism located at the magazine end of the loom and adapted to engage and move 40 downwardly the filling thread which passes from the shuttle to the fabric, so that said filling thread will clear the opening in the shuttle and move said thread out of the path of the filling detector or feeler slide as 45 it enters said opening.

I have only shown in the drawing a detached portion of the lay of a weft replenishing loom of the ordinary type, with my improvements combined therewith, sufficient 50 to enable those skilled in the art to understand the construction and operation thereof.

Referring to the drawings:—Figure 1 is 55 a front view of the right hand end of a lay, partially shown in section, on line 1, 1, Fig. 2, looking in the direction of arrow *a*, same

figure, with my improvements applied thereto. Fig. 2 is a plan view of the lay shown in Fig. 1, and a section, on line 2, 2, Fig. 1, looking in the direction of arrow *b*, same figure, and also shows one end of the breast beam, and the filling fork slide thereon, and the filling detector or feeler slide, and, Fig. 3 is a section, on line 3, 3, Fig. 1, looking in the direction of arrow *c*, same figure.

In the accompanying drawing, 1 is a portion of the loom side or end frame, 2 is the breast beam, 3 the lay, and 4 the lay sword, 5 is the reed carried on the lay, 6 the hand-rail, 7 is a stationary shuttle box on the magazine end of the loom, 8 is a shuttle, 9 a bobbin from which the weft or filling thread 9' passes to the woven fabric 10. The shuttle 8 has an opening 8' in its front wall into which, on the forward movement of the lay, the filling detector or feeler slide 11 enters to engage with the filling on the bobbin, to detect the practical or substantial exhaustion of the filling on the bobbin.

The filling detector or feeler slide 11 is suitably guided at 12 on a stand 13 secured to the loom side 1, and is connected through intermediate connections, not shown, with the weft replenishing mechanism, not shown, to operate the same in the usual and well known way, to supply fresh filling to the shuttle on the substantial exhaustion of the filling on the bobbin in the shuttle.

On the breast beam 2 is the bed 14 for the filling fork slide 15, which carries the filling fork 16, which is adapted to be engaged 90 by the filling 9' in the front of the grate 17, in the usual way.

All of the above mentioned parts may be of the usual and well known construction.

I will now describe my improvements. 95 On the filling fork slide 15 is in this instance a forwardly projecting extension 15', which carries a stud 18. On the stud 18 is pivotally mounted, to swing thereon, a filling depressor, which in this instance is made 100 in the shape of a curved plate 19, as shown in Fig. 3, preferably of sheet metal. The depressor 19 is held in its lowered position, shown in Fig. 3, by gravity, and has on its upper edge a side lug or projection 19' 105 which rests upon the filling fork slide 15. The lower and rearwardly extending portion of the plate 19 is made inclined at 19'', and said portion 19'' is adapted to engage 110 the filling thread 9' on the forward move-

ment of the lay, to move downwardly, or depress said filling thread, until it takes a position below the lower edge of the plate 19, as shown in Figs. 1 and 3.

5 The depression of the filling thread 9' on the forward movement of the lay, by the engagement of the depressor 19 therewith, causes the filling thread to move from the position shown by broken lines in Fig. 1, to 10 the position shown by full lines in said figure, so as to extend below, or clear the opening 8' in the front shuttle wall, and leave a clear space for the entrance of the filling detector or feeler slide 11 through 15 said opening, to engage the filling on the bobbin.

I have shown in the drawing and described herein my improvements in filling depressor combined with a weft replenishing loom, and more particularly with a shuttle having an opening through the front wall thereof for the entrance of a filling detector or feeler slide, but it will be understood that I do not limit my invention to the 20 use of my filling depressor or weft replenishing looms, as the same may be used on ordinary looms, which have a side filling fork stop motion, and in connection with 25 ordinary shuttles, without any opening through the wall thereof for the entrance of a filling detector or feeler.

My filling depressor will act to engage and move downwardly the filling thread,

and bring it nearer the lower ends of the tines of the filling fork, so that on the forward movement of the lay, the tines or lower ends of the filling fork will be sure to be engaged and tilted by the filling.

It will be understood that the details of construction of my improvements may be 35 varied if desired. The filling depressor may be mounted on the breast beam, instead of on the filling fork slide, or on some other part of the loom.

Having thus described my invention, 40 what I claim as new and desire to secure by Letters Patent is:—

In a weft replenishing loom having a filling detector located at the magazine end of the loom to feel through an opening in the 45 front wall of the shuttle and engage the filling on the bobbin therein, a filling depressor, pivotally mounted on some part of the loom at the magazine end of the loom, and provided with a curved or inclined engaging end to engage and pass over the filling on the forward movement of the lay, and depress said filling below the opening 50 in the front wall of the shuttle, and leave a clear space for the entrance of the filling 55 detector or feeler through said opening.

BENJ. F. McGUINESS.
